UNITED STATES PATENT OFFICE.

HENRI BEAU, OF PARIS, FRANCE.

HYDRAULIC APPARATUS.

1,047,489.

Specification of Letters Patent. Patented Dec. 17, 1912.

Application filed March 25, 1911. Serial No. 616,971.

To all whom it may concern:

Be it known that I, HENRI BEAU, a citizen of the Republic of France, and resident of 46 Rue du Ranelagh, Paris, Seine, France, 5 have invented Improvements in or Connected with Hydraulic Apparatus, of which the following is a specification.

This invention has for its object a hydraulic apparatus which produces the maximum effect relatively to a given work.

Various forms of pumps embodying the principle of the invention are illustrated by way of example in the accompanying drawing in which:

15 Figures 1, 1^a and 1^b together show a vertical section of one embodiment of the invention, Figs. 2 2^a and 2^b together show a side elevation thereof, Fig. 3 is a section of a special chamber applicable to all the embodiments, Fig. 4 illustrates a modified form 20 of lifting pump with horizontal channel and air reservoir. Fig. 5 shows another direct lifting device, Fig. 6 shows the adaptation of the chamber of Fig. 3 to the embodiment 25 illustrated in Fig. 4. Fig. 7 shows the application of this same chamber to the embodiment shown in Fig. 5.

Referring to Figs. 1 1^a and 1^b the pump consists broadly of the following parts: *a* is a column which opens at the base in a strainer 30 closed by a spring valve, its upper part being connected with the pump body *b* in which a piston *c* moves as a result of various efforts as hereinafter explained; the piston 35 is connected with the rod *d* forming a frame at *e*. In this frame two rollers *f* are arranged; between them a cam *g* keyed to the driving shaft *h* acts; this shaft is provided with a regulating fly wheel and the shaft is 40 rotated by means of a crank *i*. A second cam *j* is mounted on the shaft *h* and controls the opening of a conical compression valve *k* upon which a spring *l* bears; this spring presses it upon its seat during the 45 compression of the liquid column. The tension of the spring *l* should be equal to or slightly greater than the maximum excess pressure of the air reservoir *v*¹. This valve is arranged in the interior of the water flow 50 reservoir *m* arranged at the upper part of the column *a*. Beneath the valve *k* there is arranged a valve constituted by a metallic grating *a*³ against which an india-rubber membrane *b*³ is placed. When the liquid 55 column abandoned by the piston continues

to descend under the influence of its inertia the membrane *b*³ is drawn toward the interior of the column *a* under the influence of atmospheric pressure and when the column of water ascends this membrane presses 60 against the grating *a*³. This arrangement obviates the prejudicial effects which might occur in the column *a* owing to the vacuum produced by the liquid in movement. The chamber *n* is arranged above the main body 65 *o* which contains two india-rubber membranes *p* *q* clamped by the cheeks *r*, the displacement of which is limited by gratings *s*. On each side of the main body two air pockets are thus formed; a small pocket *t* which 70 can be inflated through a small tube *u* opening at the upper part of the pump and a large pocket *v* in communication with an air reservoir *v*¹ serving to balance the pressure of the water in the column *a*. This 75 pocket may be supplied with compressed air through a pipe *x*. The foot valve consists of a metal plate *c*¹ resting upon a seat *d*¹ under the influence of a spring *a*¹ arranged inside the strainer *a*². A metal washer *e*¹ 80 is arranged on this valve *c*¹ and upon this washer a disk *y* of india rubber is held by means of an upper plate *g*¹ tightened by a nut. The pliable edges of the india rubber disk rest resiliently upon a seat *z* thus forming a hermetic joint.

The cam *g* should be designed and its speed of rotation calculated in such a manner as to fulfil the following conditions: (1) It should act upon the rollers *f* tangentially and consequently without initial velocity when the swell of the cam is in its highest position. (2) A uniformly accelerated velocity should be given to the rollers 90 and it should be proportional to the time 95 and to the square of the distances traversed and consequently to the length of the circular arc described by the cam in movement. (3) The column should be afforded the time necessary for effecting its several movements 100 and to resume the condition of repose before the rollers are again acted upon. (4) For acting upon the rollers it should not exceed the velocity corresponding to the displacement of the liquid column *a* in such a manner that its molecules are always under pressure throughout the entire duration of the displacement. (5) It should also not exceed a speed corresponding to obtaining a 105 suitable efficiency from the inertia of the 110

liquid column. (6) It should impart to the rollers a travel proportionate to that which is to be effected by the liquid column.

The pump in Fig. 1 operates in the following manner: The tube a being full of water and the air chambers t and v inflated to the pressure corresponding to the height of the column of water to be raised (that is to say the pump being primed) the piston 10 is caused to descend and in forcing before it the column of water it imparts to the latter a uniformly accelerated movement until the cam leaves the piston which then rests upon its seat and the valve h opens under the influence of the cam j . The membrane g of the pocket v becomes applied against the grating s which stops it. The column of water has thus acquired a *vis viva* in the downward direction which acts freely under 15 the influence of the atmospheric pressure exerted by the intermediary of the membrane b^3 so long as the valve h is not fully open. The work produced by this *vis viva* is stored in the small air chamber t in the 20 form of an excess pressure. The excess air pressure stored in this air pocket t projects the column of water upward. As long as the column of water thus projected is in movement, the pressure upon the top of the 25 foot valve y is zero while beneath it the pressure is equal to that produced by the height of the level of water above the valve. The latter thus opens permitting of the passage of the water necessary for filling the 30 vacuum produced by the upward movement of the column of water.

Two other devices based upon the same principle are represented in Figs. 4 and 5.

The pump in Fig. 4 is composed of the 35 following parts: a is the column which opens on one side and at a certain height into a reservoir b^1 and on the other side at the base of a pump body c^1 . A piston d^1 provided with a valve e^1 with spring f^1 and opening 40 downward is displaceable in this pump body. It is connected with the rod g^1 forming a frame at e ; in this frame a roller f is mounted and the cam g controlled by the flywheel l^1 acts against this roller; a counter spring 45 m^1 bears upon the piston d^1 and upon the cap of the pump body. A second spring q^1 forming a buffer surrounds the rod g^1 and bears upon the cap of the pump body under the action of the thrust of the liquid in 50 movement as soon as the cam g has left the roller f . The springs m^1 and q^1 fulfil the same functions as the air pockets t and v in the type of pump shown in Fig. 1. After it has passed through the yoke n^1 the top of 55 the rod g^1 carries a stop o^1 for limiting the stroke of the piston and a counter spring p^1 . The pump body is immersed in the liquid to be pumped. A conduit r^1 extends upward from the base of the reservoir b^1 and carries 60 the water in s^1 to an indefinite height. The

tension of the spring m^1 should be calculated in such a manner as to balance the pressure in b^1 . It should be so flexible that its excess tension due to the displacement caused by the cam can be regarded as practically *nil*, that is to say its coefficient of compression per cm. of compression should be as low as possible. The spring g^1 should be of such a kind that is able to store the work corresponding to the mass and to the 70 velocity of the liquid column a , taking into account that the compression resulting from the accumulation of this work should be at least equal to three times the pressure in b^1 , that is to say, that its coefficient of compression per cm. of compression should be very 75 large without nevertheless exceeding the strength of the parts of the apparatus. As regards the spring f it should be of such a nature as to apply the valve e upon its seat 80 at the moment at which the liquid column completes its movement in the direction of the arrow y^1 .

The operation of this pump is as follows: Assume the pump to be primed the pump 90 body immersed in the mass to be pumped, the piston at the end of its stroke and a certain pressure to have been already obtained in b^1 . Beneath this pressure the column of water contained in a tends to travel in the 95 direction of x^1 and to press the piston d^1 upward. This piston is raised by the rod g^1 under the influence of the cam g . The water in the column a follows the piston in its displacement under the influence of the 100 pressure stored in its molecules with the same velocity as itself, until the moment at which the cam g having left the roller f it continues its movement by virtue of its acquired velocity and causes the spring q^1 105 to strike against the cap of the pump body and compresses it until its *vis viva* is exhausted. The springs m^1 and q^1 then extend successively and displace the column of water in the direction indicated by the 110 arrow y^1 . A shoulder o^1 on the rod g^1 striking against the spring p^1 supported by the yoke n^1 the piston stops but the column a continues its movement under the influence of its velocity. The vacuum resulting in the 115 pump body c^1 is filled by a cylinder charge of liquid coming from the mass to be pumped beneath the pressure of which the valve e^1 has opened. The column a having finished its movement the valve e^1 closes and the excess pressure obtained in b^1 forces a 120 certain quantity of liquid into a . At this moment the conditions obtained at the commencement of operations have been re-established and the same phenomena are reproduced. 125

In the pump shown in Fig. 5 the action is precisely the same but the intermediate air reservoir being omitted the water enters s^1 intermittently instead of arriving con- 130

tinuously. The cam and the piston and the devices that they operate can likewise be replaced by any other means for producing movement provided that it fulfills the conditions of pressure acceleration of velocity and duration indicated for the cam.

Having now particularly described and ascertained the nature of my said invention and in what manner the same is to be performed, I declare that what I claim is:—

A hydraulic apparatus comprising a vertical pipe adapted to contain a column of liquid; upper and lower chambers formed at the lower end of the pipe and forming a continuation thereof; gratings in the sides of the lower chamber; yieldable membranes covering the outer face of said gratings; pockets covering said membranes; an air

reservoir communicating with said pockets; means for forcing downwardly said column 20 of water against the pressure of the membranes and the air of the air reservoir, whereby the column is caused to rebound; a clack valve at the upper part of the pipe for permitting the efflux of the water when the 25 column rebounds; and means for holding the clack valve closed when the column is being forced downwardly.

In testimony whereof I affix my signature in presence of witnesses.

HENRI BEAU.
